UNITED STATES PATENT OFFICE.

WILHELM B. BRONANDER, OF MONTCLAIR, NEW JERSEY, ASSIGNOR TO INTERNATIONAL CIGAR MACHINERY COMPANY, A CORPORATION OF NEW JERSEY.

CIGAR-FILLER FEED.

Application filed December 22, 1923. Serial No. 682,162.

To all whom it may concern:

Be it known that I, WILHELM B. BRONANDER, a citizen of the United States, residing at Montclair, county of Essex, and State of New Jersey, have invented a new and useful Improvement in Cigar-Filler Feeds, of which the following is a specification.

This invention relates to an improvement in cigar filler feeds, and it has for its main object the production of a more efficient and more economical device of this general character. A further object of the invention is the production of a device capable of use in connection with the usual feed belt of known cigar machines. With these and other objects not specifically mentioned in view, the invention consists in certain combinations and constructions which will be hereinafter fully described and then specifically set forth in the claims hereunto appended.

In the accompanying drawings, which form a part of this specification and in which like characters of reference indicate the same or like parts, Fig. 1 is a side elevation, partly in section, of a device constructed in accordance with the invention; Figs. 2 and 3 are similar views showing some of the parts of Fig. 1 in different positions, and omitting some of the parts; and Fig. 4 is a front elevation, partly in section, of the device shown in Figs. 1 to 3 inclusive.

In carrying the invention into effect, there is provided a plurality of presser wheels adapted to act upon a sheet of filler advanced by the feed belt of a cigar machine, and a plurality of feeding fingers interspersed among said wheels and acting independently upon the sheet of filler, and means for producing a four-way feeding movement of the lower or active ends of said fingers. In the best constructions, said means includes a cam actuated floating bar upon which said fingers are fulcrumed and a cam actuated rocking frame and a plurality of springs normally holding said fingers against said frame but permitting said fingers

to independently yield in the event of an excess of filler within their range of action. The above mentioned parts may be widely varied in construction within the scope of the claims, for the particular device selected to illustrate the invention is but one of many possible concrete embodiments of the same. The invention therefore is not to be restricted to the precise details of the structure shown and described.

Referring to the drawings, there is provided a bed 5 which is a part of the cigar machine in connection with which the present device is used. This cigar machine is provided with a feed belt 6, the construction and operation of which is well known, lies outside the scope of the present invention, and therefore needs no detailed description. The upper run of this feed belt, upon which filler is spread by the operator, has the usual intermittent forwardly feeding movement which brings the filler material within the range of action of a plurality of presser wheels 7 each of which is provided with a pair of trunnions 8 engaging slots 9 in a grid 10 supported by a bar 11 extending across the cigar machine. The pressure exerted by these wheels is governed solely by their weight, and they act upon the advancing sheet of filler to compact the same to a limited extent on the feed belt 6.

Interspersed among the wheels 7 is a plurality of feeding fingers 12 fulcrumed at 13 to a rocking arm 14, which in turn is fulcrumed on a shaft 15 journaled in suitable bearings in a frame 16 supported by the main frame of the cigar machine. On one of its ends the shaft 15 is provided with an arm 17, and this arm 17 carries a cam bowl 18 tracking in a cam groove 19 formed in one face of a cam 20. This cam is mounted on a short shaft 21 journaled in suitable bearings in the frame 16. This shaft is driven by means of a short universal link 22 deriving its motion from a shaft 23 journaled in a bracket 24 rising from the bed 5 before referred to. The shaft 23 is driven

by means of a sprocket 25 deriving its motion, through the agency of a sprocket chain, from a sprocket on one of the shafts of the cigar machine in connection with which the device is used. The shaft 23 and the cam 20 rotate continuously, and the cam groove 19 is adapted to produce at the proper time a rocking movement of the shaft 15 which raises and lowers the feeding fingers 12. 10 The upper part of all of the fingers 12 normally rests against rollers 26 rotatable on a bar 27 supported by a rocking frame 28 which frame has a leg 29 pivoted on a stud 30 fast to one side of the frame 16; the frame 28 also has a second leg 31 fulcrumed on a stud 32 supported on the other side of the frame 16. The leg 31 has an integral arm 33 which carries a cam bowl 34 tracking in a groove 35 formed in the cam 20 before referred to. The upper end of each feed finger 12 is provided with a series of notches 36 into one of which is hooked one end of a spring 37, the other end of the spring being hooked into suitable apertures in a forwardly extending web 38 formed integrally with the frame 28.

The cam groove 35 is designed to rock the frame 28 on its fulcrum 32 at the proper time. 30 Assuming that the parts are in the position shown in Fig. 1, rotation of the cam 20 causes the lower end of the feeding fingers to move downwardly and engage the filler material on the feed belt 6, as shown in Fig. 35. 2. Further movement of the cam causes the frame 28 to rock on its fulcrum, the springs 37 normally holding the upper end of each feeding finger against one of the rollers 26; thus the lower ends of the feeding fingers are moved to the position shown in Fig. 3, under normal conditions. If, however, there is an excess of tobacco in the wake of any one of the fingers, the resistance offered thereby will cause the spring of that finger 40 to yield so that the part of the sheet of filler on the belt 6 in the wake of that finger will not be fed forward as far as the rest of the sheet. By this means, any error of the feeding operator in placing too much filler on one part of the belt 6 is corrected before the sheet is delivered from the feeding device. When the parts reach the position shown in Fig. 3, the cam grooves cause the lower end of the feeding fingers to be 50 lifted, and then move backwardly along the line indicated in Fig. 3 by the dotted line having direction arrow heads placed thereon.

Beyond the mechanism so far described is 60 a knife 39 carried by a frame 40 which is vertically reciprocated by a cam and suitable connections carried by the cigar machine in connection with which the device is used. The particular construction of this 65 knife and its operating mechanism is old

and well known, lies outside the present invention, and therefore needs no detailed description. It functions to sever individual charges from the sheet of filler advanced by the feed belt 6, and corrected, when 70 correction is needed, by the mechanism herein described.

In view of the foregoing, a detailed description of the operation of the device is deemed unnecessary and is therefore omitted 75 in the interest of brevity.

What is claimed is:

1. In a cigar filler feed, the combination with a plurality of presser wheels, of a plurality of feeding fingers interspersed among said wheels, and means for producing a four-way feeding movement of the lower ends of said fingers. 80

2. In a cigar filler feed, the combination with a plurality of presser wheels, of a plurality of feeding fingers interspersed among said wheels, and means for producing a four-way feeding movement of the lower ends of said fingers, the pressure exerted by said wheels being governed by their weight. 90

3. In a cigar filler feed, the combination with a plurality of presser wheels, of a plurality of feeding fingers interspersed among said wheels, and means for producing a four-way feeding movement of the lower ends of said fingers, said means including a cam-actuated floating bar upon which said fingers are fulcrumed. 95

4. In a cigar filler feed, the combination with a plurality of presser wheels, of a plurality of feeding fingers interspersed among said wheels, and means for producing a four-way feeding movement of the lower ends of said fingers, said means including a cam-actuated rocking frame against which 105 said fingers normally rest. 100

5. In a cigar filler feed, the combination with a plurality of presser wheels, of a plurality of feeding fingers interspersed among said wheels, and means for producing a 110 four-way feeding movement of the lower ends of said fingers, said means including a cam-actuated rocking frame and a plurality of springs normally holding said fingers against said frame. 115

6. In a cigar filler feed, the combination with a plurality of presser wheels, of a plurality of feeding fingers interspersed among said wheels, and means for producing a four-way feeding movement of the lower 120 ends of said fingers, said means including a cam-actuated floating bar upon which said fingers are fulcrumed and a cam-actuated rocking frame and a plurality of springs normally holding said fingers against said frame. 125

7. In a cigar filler feed, the combination with a plurality of presser wheels, of a plurality of feeding fingers interspersed among said wheels, means for producing a four-way 130

feeding movement of the lower ends of said fingers, and means for feeding filler into the range of action of said wheels and fingers.

8. In a cigar filler feed, the combination
5 with a plurality of presser wheels, of a plurality of feeding fingers interspersed among said wheels, means for producing a four-

way feeding movement of the lower ends of said fingers, and means beyond said wheels and fingers for severing individual charges 10 from the filler.

In testimony whereof, I have signed my name to this specification.

WILHELM B. BRONANDER.
